(57) **CLAIM**

The ornamental design for an agricultural work vehicle, substantially as shown and described.

DESCRIPTION

FIG. 1 is a front perspective view of an agricultural work vehicle;

FIG. 2 is a back perspective view of the agricultural work vehicle;

FIG. 3 is a top view of the agricultural work vehicle;

FIG. 4 is a right side view of the agricultural work vehicle;

FIG. 5 is a left side view of the agricultural work vehicle;

FIG. 6 is a front view of the agricultural work vehicle; and,

FIG. 7 is a back view of the agricultural work vehicle. Phantom lines, where utilized, are for illustrative purposes only and form no part of the claimed design.
